CLAIM

The ornamental design for a heart rate monitor, as shown and described.

DESCRIPTION

The claimed heart rate monitor, for example, may be used for detecting or monitoring heart rate via a rechargeable pod that is releasably coupled to a wrist strap (e.g., as set forth in related U.S. Provisional Patent Application No. 63/146,436 filed Feb. 5, 2021, which is incorporated herein by reference in its entirety).

FIG. 1 is a rear, right, and top perspective view of a wrist strap of a heart rate monitor embodying the new design;

FIG. 2 is a front, left, and bottom perspective view thereof;

FIG. 3 is a top plan view thereof;

FIG. 4 is a bottom plan view thereof;

FIG. 5 is a right side view thereof;

FIG. 6 is a front elevational view thereof;

FIG. 7 is a rear elevational view thereof;

FIG. 8 is a left side view thereof;

FIG. 9 is a rear, right, and top perspective view of a charger of the heart rate monitor embodying the new design;

FIG. 10 is a front, left, and bottom perspective view thereof;

FIG. 11 is a top plan view thereof;

FIG. 12 is a bottom plan view thereof;

FIG. 13 is a front elevational view thereof;

FIG. 14 is a rear elevational view thereof;

FIG. 15 is a left side view thereof;

FIG. 16 is a right side view thereof;

FIG. 17 is a rear, right, and top perspective view of a pod of the heart rate monitor embodying the new design;

FIG. 18 is a front, left, and bottom perspective view thereof;

FIG. 19 is a top plan view thereof;

FIG. 20 is a bottom plan view thereof;

FIG. 21 is a right side view thereof;

FIG. 22 is a left side view thereof;

FIG. 23 is a front elevational view thereof;

FIG. 24 is a rear elevational view thereof;

FIG. 25 is a front, right, and top perspective view of the heart rate monitor embodying the new design;

FIG. 26 is a front, right, and bottom perspective view thereof;

FIG. 27 is a top plan view thereof;

FIG. 28 is a bottom plan view thereof;

FIG. 29 is a right side view thereof;

FIG. 30 is a left side view thereof;

FIG. 31 is a rear elevational view thereof; and,

FIG. 32 is a front elevational view thereof.

The broken lines are shown for the purpose of illustrating portions of the heart rate monitor and environmental matter that form no part of the claimed design. The charger of the heart rate monitor is shown with a symbolic break in its length and the appearance of any portion between the break lines forms no part of the claimed design. The dot-dash broken lines define the bounds of the claimed design and form no part thereof.
